CASEMENT SASH ADJUSTER OR THE LIKE

Bert E. Bartholomew, Balboa Island, Calif.

Application May 16, 1939, Serial No. 273,936

11 Claims. (Cl. 74—504)

My invention relates to a drive or operating mechanism or adjuster to develop a rotation of a screw shaft, a rotating shaft or a rotating gear which is located in a more or less inaccessible position due to its elevation above the operator. My invention is of a type having utility for opening and closing casement or similar pivoted sash, a set of louvers or mechanism for rolling in and unrolling awnings or the like. My invention however is particularly designed for operation on sash adjusters for swing casement sash as exemplified in my U. S. Patent No. 1,732,709, issued October 27, 1929.

It is quite a common procedure in large buildings such as schools, auditoriums, church buildings and the like to have pivoted casement or similar type of sash at a considerable elevation above the floor and in which these are operated for opening and closing by some type of a screw or rotating shaft type of device. A main object and feature of my invention therefor involves a construction of a rotational drive mechanism which may be removably connected to the operating shaft and actuated from the floor. A feature of this construction is providing a rotating driving assembly with a plug-like rotating or driving shaft mounted on a housing attached to the upper end of a long pole in which the rotating plug or drive shaft is actuated in its rotational movement by a sprocket gear having a chain or the equivalent, the chain extending downwardly within convenient reach of the operator. Another characteristic of my invention is an interchangeable construction by which when desired the drive mechanism may be directly attached to part of the sash adjuster and have the chain suspended from the overhead drive sprocket whereby the rotational movement may be given directly by manipulating the chain.

A further characteristic of my invention as to the portable and readily removable type of drive mechanism features a guide bracket attached to part of the mechanism of the sash adjuster or part of the equipment having the rotating driven shaft. With this I employ a long pole on the upper end of which is a complementary guide and supporting finger which may be inserted in the guide bracket and thus locate the actuating rotating plug shaft in the proper position relative to the driven shaft. A further characteristic of my invention involves a sprocket housing attached to the upper end of the long pole and preferably secured to a plate formed integral with the guide finger utilized to engage the bracket whereby in such housing I provide a ro-

tating plug type of drive shaft with the plug projecting from one side and in the housing the shaft has a sprocket mounted thereon with an endless chain taking over the sprocket and depending downwardly along the pole.

Another characteristic of my invention is having the housing with the plug shaft and sprocket chain equipment formed in a complete assembly to be removable from the finger plate and attached to part of the adjuster of the sash or the like. With this equipment I utilize a replaceable socket plug of the driven shaft or screw, such socket plug being provided with a recess to be engaged by the plug shaft rotated by the sprocket and chain. In this connection another detail feature of my invention is providing the housing so that it may be attached by screws or the like to a hinge leaf acting as a thrust plate for the rotating screw assembly, thus mounting the housing with the driving plug directly on the leaf to swing with such leaf on its pintle pin, such construction being suitable for conditions in which the pintle pin is arranged horizontally. For an equipment in which the pintle pin is vertical as on which the sash opens on a vertical hinge, the housing for the sprocket chain and plug shaft has the plug secured to the socket structure of the driven screw, hence the housing may tilt in accordance with the angular movement of the leaf on the vertical axis of its pintle, therefore by making a slight change, parts of the same equipment may be used on the upper end of a long pole for turning a shaft or may be directly connected to such shaft and have this rotated by means of a sprocket and a long endless chain.

My invention is illustrated in connection with the accompanying drawing, in which:

Fig. 1 may be considered as a vertical longitudinal section through the sash adjuster and the removable drive mechanism therefor. The section may be considered taken respectively on the section lines 1—1 of Figs. 2 and 3, in the direction of the arrows.

Fig. 2 is a front elevation of part of the sash adjuster taken in the direction of the arrow 2 of Fig. 1.

Fig. 3 is a front elevation of the removable operating mechanism for the adjuster taken in the direction of the arrow 3 of Fig. 1.

Fig. 4 is a longitudinal section of the sash adjuster similar to Fig. 1 but showing the operating and driving equipment directly connected thereto.

Fig. 5 is a front elevation taken in the direction of the arrow 5 of Fig. 4.

Referring first to the construction of Figs. 1, 2 and 3, this illustrates a window sill or other fixed horizontal structure 11 to which is attached a hinge assembly 12, such hinge assembly employs a stationary leaf plate 13 secured to the sill 11. The knuckle 14 of the hinge is provided with a pintle 15, the moving leaf plate 16 thus having a hinged connection turning on the horizontal pintle. This leaf plate has a central circular opening 17 and a plurality of threaded screw receiving sockets 18. There is also a recess 19 at the top, the contour of the leaf plate 16 preferably being as shown in Fig. 2.

A bracket 25 is formed of a plate 26 having an angular bend 27 with a lower portion 28 fitting in the recess 19 and attached to the moving hinge leaf 16 by screws 29. This bracket is made in the form of a yoke, at its outer end 30 having two arms 31 spaced apart by a converging opening 32, this being for a purpose hereunder designated.

A rotatable hollow shaft 35 has an outer tube 36 with a threaded connection to a combination thrust plug and socket 37, this being provided with an annular shoulder 38 abutting against the outer face of the leaf plate 16 and having a cylindrical portion 39 extending through the circular opening 17. A locking collar 40 is attached by a set screw, this collar fitting snugly against the inner face of the plate 16. A squared or similar socket 41 extends longitudinally through the thrust plug and socket 37, the socket being firmly attached to the tube 36 by a locked pin 42. A series of nested or telescopic screws 45 are housed and operative within the outer tube 36. This assembly may be constructed and operate and have an attachment to a sash substantially similar to that of my Patent No. 1,732,709 above noted.

The actuating or power assembly designated by the numeral 50 and illustrated particularly in Figs. 1 and 3 includes a long pole 51 by which the custodian or person operating the windows may reach to the adjusting assembly in a high elevation above the floor. A finger plate 52 has a substantial base 53 which is illustrated as provided with a screw threaded connection on the upper end of the pole 51. There is a plate section 54 with a plurality of threaded screw receiving recesses 55 and a central circular opening 56. A curved finger 57 extends upwardly from the main plate portion and terminates in a bulbous type of cross bar 58. The finger may thus be inserted in the yoke of the bracket 25 to fit between the two arms 31 with the cross bar engaging above these arms as shown in Fig. 1. The yoke thus forms a guide in bringing the drive mechanism into its operative position.

Mounted on the plate 54 I have a housing 60. This is provided with a back plate 61 with an integral outwardly extending rim 62. The back plate is attached to the plate 54 by screws 63 threaded in the recesses 55. A removable cover plate 64 is attached to the periphery of the rim 62 by screws or the like and there are circular shaft journals 65 in the cover 64 and 66 in the back plate 61. The lower portion of the rim is provided with perforations 67 for the passage of an operating chain.

The drive shaft assembly 70 includes a reduced diameter cylindrical shaft end 71 having a bearing at 68. On this is secured a sprocket wheel 72 by a key or the like. An enlarged cylindrical

portion 73 has a bearing at 66 in the back plate 61 and extends partly through the opening 56 in the plate 54. A squared or similar irregular shaped driving plug shaft 74 extends through the remainder of the opening 56 and beyond the plate 54, this being provided with a guide point 75. The drive chain 76 takes over the sprocket wheel and has the two ends passing downwardly through the openings 67.

The manner of operation and functioning of the device as so far described is as follows: Presuming it is desired to actuate the adjuster mechanism for a sash or the equivalent, the adjuster being located at a high elevation above the floor, the operator then elevates the pole in order to engage the finger 57 and the bar 58 with the yoke assembly of the bracket 25 as above indicated. Then as the pole is lowered slightly and tilted more to the vertical, the guide end 75 of the plug shaft 74 is guided and becomes inserted in the socket 41 of the plug and socket assembly 37 on account of both the plug and the socket being square in cross section or other suitable shape to interfit. A drive connection is thus obtained between the plug shaft 74 and the outer tube 36 of the hollow shaft assembly 35. Then by actuating the chain 76 the operator may rotate the sprocket wheel in either direction and thereby rotate the outer tube 36 and thereby manipulate the assembly of telescoping screws 45 to either open or close a pivoted sash or the equivalent. Manifestly when the desired adjustment is obtained the pole is shifted outwardly to a slight inclination and at the same time may be raised, thus disengaging the plug shaft 74 from the socket 41 and elevating the finger 57 and the cross bar 58 is released from the yoke bracket 25. As installations of this type are usually installed in multiple, the operator may then proceed from one sash to the other, the common actuating device of the assembly 50 being suitable for all of the connections.

Where it is desired to have the sprocket wheel and chain drive as an integral equipment with the adjusting mechanism for the sash, I modify the installation as shown in Fig. 4 in which instance as the bracket 25 is not required, this may be removed. As above mentioned, it is merely attached by the screws 29 to the hinge leaf plate 16. It is also desirable to slightly modify the thrust plug and socket assembly 37 and substitute therefor a thrust plug and socket assembly 80. This has a shoulder 81 and a short cylindrical neck 82, preferably terminating at the outer face of the hinge leaf plate 16. The housing 60 is disconnected from the assembly 50, that is, from the finger plate 52 which may be done by removing the cover plate 64 and removing the sprocket wheel 72 together with the assembled plug shaft 74. This equipment is then reassembled and connected as shown in Fig. 4, however if it is desired to have the housing rigidly attached to the hinge leaf 16, it is secured thereto by the screws 63 which are threaded into the receiving sockets 18, however in the illustration of Figs. 4 and 5, the housing assembly and the pulley is not rigidly connected to the hinge plate but mounted to allow a swivelling action. The plug shaft 74 is inserted in the socket 83 of the shorter thrust socket plug 80 and rigidly attached by replacing the pin 42, the plug having a perforation 84 to receive such pin. By this construction the plug shaft 74 becomes rigidly attached to the thrust plug and socket assembly 80 and hence to the outer tube 36 which has contained therein

the assembly of telescoping screws 45. The back plate 61 and the housing prevent disconnection of the tube assembly and the plug 89 and on account of the enlarged cylindrical portion 73 having a bearing in the back plate 61 and the cylindrical end 71 having a bearing in the cover 64, the housing is properly centered as regards the plug socket 80 and the hinged leaf 16. It is preferable to have a slight loose fit of the squared plug shaft 74 in the socket 83 as it is to have a somewhat loose fit of the wheel plug in the socket 41.

When the housing 60 and the assembled parts are not rigidly attached to the hinge leaf 16 as shown in Figs. 4 and 5, the housing with the pulley assembly may tilt as shown in Fig. 5. This allows the pintle 15 of the hinge knuckle assembly 14 to be vertical where the sash pivots on a vertical pivoting assembly as the housing may have a free rotation relative to the plug 74 and the parts to which it is attached. However where the hinge is horizontal as illustrated in Figs. 1 and 4, it is preferable to attach the housing 60 to the leaf 16 by the screws 63. It will be apparent by this construction that for each sash assembly it is necessary to have a depending chain, the chain therefore being operative to rotate the adjusting device for the sash. These chains are usually made endless and of the desired length to reach from the adjusting assembly to a convenient position to be utilized by an operator. Thus in an assembly of sash and adjusters, it is the usual practice to have a group of these arranged without the attached operating assembly and to have this mounted on a pole but where there are a few isolated sash, it is desirable to have the operating sprocket wheel and chain attached to the adjusting assembly.

Various changes may be made in the details of the construction without departing from the spirit or scope of the invention as defined in the appended claims.

I claim:

1. In a device as described in which a hinge is provided with a leaf plate and a driven shaft rotatably mounted in relation to such plate, such shaft being operative to actuate a device by rotation of such shaft combined with a gear housing, a shaft journalled therein having a sprocket wheel with an operating chain mounted on said shaft, means to connect the housing to the said leaf and a complementary plug and socket forming an operative drive connection between the shaft of the sprocket and the driven shaft.

2. In a device as described in which a hinge is provided with a leaf plate and a driven shaft rotatably mounted in relation to such plate, such shaft being operative to actuate a device by rotation of such shaft combined with a gear housing, a shaft journalled therein having a sprocket wheel with an operating chain mounted on said shaft, means to connect the housing to the said leaf and a complementary plug and socket forming an operative drive connection between the shaft of the sprocket and the driven shaft, a support for the housing, means to detachably connect such support and the leaf plate for rotating the housing in proximity to the said leaf plate for alignment of the sprocket shaft and the driven shaft.

3. In a device as described in which a hinge is provided with a leaf plate and a driven shaft rotatably mounted in relation to such plate, such shaft being operative to actuate a device by ro-

tation of such shaft combined with a gear housing, a shaft journalled therein having a sprocket wheel with an operating chain mounted on said shaft, means to connect the housing to the said leaf and a complementary plug and socket forming an operative drive connection between the shaft of the sprocket and the driven shaft, means to connect the plug and socket drive of the sprocket shaft and the driven shaft for positive transmission of rotating motion.

4. In a device as described in which a moving leaf of a hinge forms a support for a rotatable driven shaft combined with the leaf having an opening and the shaft having a socket structure fitted therein, a gear housing having a sprocket wheel shaft journalled in said housing, a sprocket on said shaft with a drive chain, a driving plug connected to said shaft and means to interengage the said plug and the socket for transmission of rotational motion from the sprocket to the driven shaft.

5. In a device as described in which a moving leaf of a hinge forms a support for a rotatable driven shaft combined with the leaf having an opening and the shaft having a socket structure fitted therein, a gear housing having a sprocket wheel shaft journalled in said housing, a sprocket on said shaft with a drive chain, a driving plug connected to said shaft and means to interengage the said plug and the socket for transmission of rotational motion from the sprocket to the driven shaft, a supporting structure for the housing with the housing detachably connected thereto, the leaf and the support having an interengaging means for aligning the plug with the socket.

6. In a device as described in which a moving leaf of a hinge forms a support for a rotatable driven shaft combined with the leaf having an opening and the shaft having a socket structure fitted therein, a gear housing having a sprocket wheel shaft journalled in said housing, a sprocket on said shaft with a drive chain, a driving plug connected to said shaft and means to interengage the said plug and the socket for transmission of rotational motion from the sprocket to the driven shaft, means forming a positive interconnection of the plug and the said socket positioning the said housing in proximity to the leaf plate whereby rotation of the sprocket and sprocket shaft produces a direct rotational drive of the said socket and the driven shaft.

7. In a device as described in which a moving hinge of a leaf forms a support for a rotatably driven shaft combined with the leaf having an opening and the shaft having a socket structure secured thereto and fitted in the said opening, a gear housing having a back plate and a cover, a sprocket wheel shaft journalled in the back plate and cover with a sprocket mounted thereon and an operating chain for the sprocket, a plug complementary in shape to the socket connected to the sprocket wheel shaft and inserted in the said socket and means retaining the housing and plug in driving relation with the said socket of the driven shaft.

8. In a device as described in which a moving hinge of a leaf forms a support for a rotatably driven shaft combined with the leaf having an opening and the shaft having a socket structure secured thereto and fitted in the said opening, a gear housing having a back plate and a cover, a sprocket wheel shaft journalled in the back plate and cover with a sprocket mounted thereon and an operating chain for the sprocket, a plug

complementary in shape to the socket connected to the sprocket wheel shaft and inserted in the said socket, and a pin securing the plug to the said socket and retaining the housing and sprocket wheel in driving relation with the said driven shaft.

9. In a device as described in which a moving hinge of a leaf forms a support for a rotatably driven shaft combined with the leaf having an opening and the shaft having a socket structure secured thereto and fitted in the said opening, a gear housing having a back plate and a cover, a sprocket wheel shaft journalled in the back plate and cover with a sprocket mounted thereon and an operating chain for the sprocket, a plug complementary in shape to the socket connected to the sprocket wheel shaft and inserted in the said socket, and means for attaching the housing to the said leaf with the plug inserted in the said socket for a driving rotational transmission from the sprocket wheel to the driven shaft.

10. In a device as described in which a moving hinge of a leaf forms a support for a rotatably driven shaft combined with the leaf having an opening and the shaft having a socket structure secured thereto and fitted in the said opening, a gear housing having a back plate and a cover, a sprocket wheel shaft journalled in the back plate and cover with a sprocket mounted thereon and an operating chain for the sprocket, a plug complementary in shape to the socket con-

nected to the sprocket wheel shaft and inserted in the said socket, a finger plate secured to a pole, means attaching the housing to the said finger plate, such plate having an opening through which the plug extends and interconnecting guide elements, one mounted on the leaf and the other on the finger plate for centering the plug in relation to the socket for rotational driving of the driven shaft by rotation of the sprocket.

11. In a device as described in which a moving hinge of a leaf forms a support for a rotatably driven shaft combined with the leaf having an opening and the shaft having a socket structure secured thereto and fitted in the said opening, a gear housing having a back plate and a cover, a sprocket wheel shaft journalled in the back plate and a cover with a sprocket mounted thereon and an operating chain for the sprocket, a plug complementary in shape to the socket connected to the sprocket wheel shaft and inserted in the said socket, a yoke attached to the hinge leaf and extending thereabove, a finger plate attached to a pole and having an upwardly extending finger with a bar to engage the said yoke, the said finger plate having an opening, means attaching the housing to the finger plate with the plug extending through the opening thereof, the said yoke and finger positioning the plug in the said socket in driving relation for transmission of rotation from the sprocket to the said driven shaft.

BERT E. BARTHOLOMEW.
